(57) **CLAIM**

The ornamental design for a coffee grinder, as shown and described.

DESCRIPTION

1. Coffee grinder

1.1 : Perspective

1.2 : Left

1.3 : Right

1.4 : Front

1.5 : Back

1.6 : Top

1.7 : Bottom

Fig. 1.1 is a perspective view of the design; fig. 1.2 is a left view thereof; fig. 1.3 is a right view thereof; fig. 1.4 is a front view thereof; fig. 1.5 is a rear view thereof; fig. 1.6 is a top view thereof; fig. 1.7 is a bottom view thereof.

The broken lines shown in the drawings illustrate portions of the article that form no part of the claimed design.

1 Claim, 7 Drawing Sheets
